UNITED STATES PATENT OFFICE

GEORGE HOLZWORTH, OF HALIFAX, MASSACHUSETTS

DESIGN FOR A FLOWER HOLDER OR SIMILAR ARTICLE

Application filed October 21, 1930. Serial No. 37,339. Term of patent 3½ years.

To all whom it may concern:

Be it known that I, GEORGE HOLZWORTH, a citizen of the United States, residing at South Street, Halifax, in the county of Plymouth and State of Massachusetts, have invented a new, original, and ornamental Design for Flower Holders or Similar Articles, of which the following is a specification, reference being had to the accompanying drawing, forming a part thereof.

The figure is a perspective view of a flower holder showing my new design.

I claim:

The ornamental design for a flower holder or similar article as shown.

GEORGE HOLZWORTH.
